UNITED STATES PATENT OFFICE.

SELDEN P. HOVEY, OF LOS ANGELES, CALIFORNIA, ASSIGNOR OF ONE-HALF TO JAMES C. SPANN, OF LOS ANGELES, CALIFORNIA.

COMBINATION-LOCK.

1,107,793.

Specification of Letters Patent. Patented Aug. 18, 1914.

Application filed June 11, 1913. Serial No. 773,012.

To all whom it may concern:

Be it known that I, SELDEN P. HOVEY, a citizen of the United States, residing at the city of Los Angeles, county of Los Angeles, 5 State of California, have invented new and useful Improvements in Combination-Locks, of which the following is the specification.

My invention has relation to permutation locks and is designed primarily for use on 10 automobiles and like vehicles to prevent the same being operated by unauthorized persons, and the object thereof is to provide a simple and efficient lock for that purpose.

In the present instance, I have shown my 15 device as applied to the clutch lever of an automobile and will describe it as so applied, but it will be understood that I do not limit myself to such application. I accomplish this object by the device described herein 20 and illustrated in the accompanying drawings forming a part hereof in which:

Figure 1 is a diagrammatic view of my device as applied to an automobile. Fig. 2 is a front elevation of Fig. 1. Fig. 3 is a 25 rear elevation of the lock with the cover removed. Fig. 4 is a section on the line 4—4 Fig. 3. Fig. 5 is a central vertical section of Fig. 3. Fig. 6 is a top plan partly 30 broken away and parts removed for clearness of illustration. Figs. 7 and 8 are details of the locking member and its parts.

In the drawings 10 is the lock case which may be of any suitable size or shape, preferably rectangular, in one end of which are 35 dove-tailed slots 11 and 12 longitudinally thereof. Slide blocks 13 and 14 are slidably mounted in slots 11 and 12.

On the inner surface of the casing 10 at 40 the end opposite slots 11 and 12 at a distance from the front of the casing is rigidly secured a guide block 15 having a groove 16 therein. A similar block 17 is mounted in the casing adjacent the other end thereof and has a groove 18 therein. These blocks 45 extend from side to side of the casing. A rectangular frame 19 is slidably mounted between blocks 15 and 17 to slide horizontally. The side rails of frame 19 have grooves 20 and 21 therein. A rectangular frame 22 is slidably mounted between the side rails 20 and 21 of frame 19 and slide 50 vertically therein. A rectangular frame 23 is mounted in grooves in the top and bottom rails of frame 22 and is adjustable horizontally by screws 24 and 25. A rectangular

locking block 26 is mounted in frame 23 in grooves in the side rails thereof and is adjustable vertically by screws 27 and 28. Block 26 has a port or opening 29 centrally thereof.

A locking bar 30, having one of its ends 30^a turned outwardly to project away from block 26, is pivotally mounted near said end 30^a upon said block parallel with the face thereof at one side of opening 29 and has its longer leg adapted to project over said opening and obstruct the same when the device is in a locked position. A coil spring 30^b having one end secured to block 26 and the other end secured to bar 30 between the pivot and the out-turned end 30^a serves to retain said bar in its locked position. (See Figs. 3 and 7.) The other end of bar 30 is supported in a bracket 30^c secured upon block 26. A flat spring 31 is also mounted 75 on block 26 at an angle to bar 30 and is adapted to have one end extending across opening 29 and to retain bar 30 in an inoperative position. Secured to one side of the top rail of frame 22 and extending upwardly therefrom is an inverted T-shaped guide bar 32 having a slot 33 therein. A guide pin 34 extends through slot 33 and is secured in block 17. An elevating member 35 having a slot 36 angularly disposed 80 therein is secured to slide block 14 by screws or other means. A pin 37 extends through slot 36 and is rigidly secured to the upper end of bar 32, so that when the block 14 is moved in either direction guide pin 37 traveling in slot 36 will raise or lower frame 22. A bracket 38 is secured to the underside of block 13 to the end of which is pivotally mounted a link 39. The other end of link 39 is pivotally secured to the upper end of adjusting bar 40, the other end of which is pivotally mounted on the side of block 15. Adjusting bar 40 has a slot 41 cut therein near the center thereof in which is received a pin 42. Pin 42 extends through slot 41 and is rigidly secured in one side of frame 19 so that when block 13 is moved in either direction bar 40 will, by means of pin 42, cause frame 19 to move horizontally. A releasing bar 43 is pivotally mounted between the sides of casing 10 adjacent the rear side thereof and a little below the center thereof. This bar is provided with a slot 44 longitudinally thereof and permits the adjustment of releasing trip 45 by means of ball 110

45^a to change the combination when desired as hereafter explained. Bar 43 has secured thereon at one end thereof an outwardly extending lug or arm 46 to which is pivotally secured the lower end of a releasing rod 47 which rod extends upwardly and passes through bearings 48 and 49 secured to one side of casing 10 and projects through the top of the casing. Suitable connections will be provided from the outer end of this rod to the desired place of operation.

A locking bolt 50 is slidably mounted in guide blocks 51 and 52 secured to casing 10 and the outer U-shaped end projects through a slot 53 therein when the device is in a locked position. The inner end of bolt 50 is provided centrally thereof with a stud or pin 54 which is adapted to enter opening 29 in block 26 when the same is brought into register therewith. An unlocking rod 55 is mounted in bearing 56 in the front of casing 10 and has the upper end extending through the top of the casing and is then bent to form a crank 57. The other end of rod 55 has a similar crank 58 thereon at a right angle to crank 57, the end of which is received in a slot 59 in bolt 50 so that when rod 55 is rotated by means of crank 57, crank 58 will move bolt 50 backward or forward to lock or unlock the device. Secured to rod 55 near the lower side of the top of casing 10 and preferably integral therewith is an arm 60 which is oppositely disposed from crank 57. Arm 60 is connected by a link 61 to one end of a rocking lever 62 pivotally mounted in a bearing 63 secured to the side of casing 10 near the top thereof. The other end of rocking lever 62 extends rearwardly and terminates in a hook 64 which hook is adapted to be received in the hooked end of a bracket 65 secured to the cover 66. L-shaped brackets 67 are also secured to cover 66 at the lower corners thereof and have slots 68 in the projecting legs thereof which are hooked over screws or studs 69 secured to the sides of the casing to secure the lower end of the cover in position. A stop block 70 is secured to the cover at a point opposite bracket 65.

50 When used on an automobile, the casing of my device will be attached to the floor of the car on the underside thereof or other convenient place so that the starting clutch lever 71 will pass alongside of the casing as shown in Figs. 1 and 2. This lever will be provided with slots or grooves 72 and 73 in the edges thereof which are adapted to be straddled by the U-shaped end of the locking bolt and is prevented thereby from being moved longitudinally.

Blocks 13 and 14 will be connected by rods 74 and 75 with operating handles or levers 76 and 77 which are pivotally mounted on a semi-circular indicator plate 78 secured to the dashboard 79. This plate will

have marked on the circular edge thereof a series of notches (not shown) which will be numbered. Levers 76 and 77 will each have a notch (not shown) on the upper surface thereof which will be adapted to register with the notches in the indicator plate.

In the operation of my lock with the device in a locked position, should it be desired to unlock the same the lever 76 will first be moved upwardly or downwardly as required by the combination then in effect. This will cause block 14 to be moved in a similar direction carrying elevating member 35 with it and by means of pin 37 traveling in slot 36 will elevate or lower frame 22, to bring the outwardly projecting end 30^a of bar 30 to a plane just below the plane of the end of trip 45. Lever 77 will next be operated in like manner to lever 76. This will cause block 13 to be moved in the same manner as block 14. Block 13 will carry bracket 38 with it and by means of link 39 will rock adjusting bar 40 on its pivot and pin 42 traveling in slot 41 of said adjusting bar will move frame 20 to a position so that the end 30^a of bar 30 will be directly under the end of trip 45. Pressure will then be applied to the top of releasing bar 47 to move the same downwardly which will, by means of lug or arm 46 cause bar 43 to be rocked thereby causing the end of trip 45 to strike and depress the end 30^a of bar 30. This causes bar 30 to be rocked on its pivot and elevate the other end thereof which uncovers opening 29. As soon as the end of bar 30 is sufficiently elevated spring 31 will snap under the elevated end and prevent said end from returning to its normal position. Lever 76 will then be operated as before described to raise or lower frame 22 the desired amount to bring the opening in block 26 into register in a horizontal plane with stud 54. Lever 77 will then be operated as before described to move frame 20 horizontally to bring the opening in the block 26 into register with stud 54 in a vertical plane. Unlocking rod 55 is then rotated by means of crank 57 which will cause crank 58 traveling in slot 59 to withdraw locking bolt 50 from contact with the clutch lever of the machine. As locking bolt 50 is moved inwardly pin 54 will enter and pass through the opening in block 26 and will engage and push the end of spring 31 from under the end of bar 30 and allow said bar to drop a short distance and rest upon said pin. Bar 30 will only drop a sufficient distance to prevent spring 31 moving under the end thereof when the pin 54 is withdrawn from the opening in block 26. When the lock is again locked and the locking bolt is moved to project out of the opening 53 in casing 10 pin 54 will be withdrawn from the opening in block 26 which allows bar 30 to be returned to its

normal position by spring 30^b to again obstruct said opening and prevent the device being unlocked. When it is desired to change the combination bolt 45^a is loosened 5 and trip 45 is then free to be moved in either direction the desired distance when it is again tightened. Block 26 is moved in either direction vertically in frame 23 by means of screws 27 and 28. Frame 23 is 10 moved in either direction in frame 22 by means of screws 24 and 25. Adjusting the positions of frame 23 and block 26 and trip 45 requires that blocks 13 and 14 be moved a greater or less distance in either direction 15 and changes the combination of the lock.

Having described my invention what I claim is:

1. In a combination lock the combination of a casing; a series of rectangular frames 20 slidably mounted, one within the other, in said casing; a locking block having an opening therethrough mounted in the inner one of said frames and adjustable therein; a locking bolt slidably mounted in said casing at right angles to the locking block, said bolt being adapted to have one end projected through a slot in the side of the casing when the lock is operative, and the other end projected through the opening in the 25 block when the lock is inoperative; means to bring the opening in the locking block into register with the end of the locking bolt; and means to project the end of said locking bolt through the opening in said 30 block to release the lock.

2. A combination locking comprising a casing having a slot in one side thereof; a nest of rectangular frames slidably mounted in said casing transversely thereof, said 40 frames being slidable at right angles to each other; a locking block having an opening therethrough adjustably mounted in the inner one of said frames; a locking bolt slidably mounted in the casing at a right 45 angle to the locking block adapted to project through the opening in the side of the casing when in an operative position and through the opening in the locking block when in an inoperative position; means to cause the opening in the locking block to 50 register with the end of the locking bolt; and means to cause the end of said bolt to project through the said opening in the block to release the lock.

- 55 3. In a lock a casing having a detachable cover and a slot in one side; two blocks having tracks in the opposed faces thereof mounted in the casing transversely thereof

one above the other; an outer rectangular frame having grooves in the sides thereof 60 mounted to slide horizontally between said tracks; an inner rectangular frame mounted to slide vertically in said last frame; an adjusting frame mounted in said inner frame; a locking block having an opening 65 extending centrally therethrough adjustably mounted in said adjusting frame; a locking bar adapted to cover the opening in the locking block mounted pivotally on the locking block; a locking bolt slidably mounted 70 in the casing at a right angle to the locking block and being adapted to have the outer end projected through the opening in the side of the case when locked and the inner end project through the opening in the locking block when unlocked; means to cause 75 the locking bar to uncover the opening in the block; means to cause said frames to bring the opening in the locking block into register with the inner end of the locking bolt; and means to slide said locking bolt to lock or unlock the lock when desired.

4. A lock for securing the starting lever of an automobile comprising a casing having a slot in one side thereof and two slots in 85 one end thereof; a nest of rectangular frames slidably mounted in said casing transversely thereof, said frames being slideable at right angles to each other; a locking block having an opening therethrough adjustably 90 mounted in the inner one of said frames; a locking bolt slidably mounted in the casing at a right angle to the locking block, said bolt having a U-shaped end adapted to project through the opening in the side of the 95 casing and engage a starting lever to prevent movement of the same when the lock is locked and being adapted to have the other end projected through the opening in the locking block to release the said lever when 100 the lock is unlocked; means to cause the opening in the locking block to register with the end of the locking bolt; and means to cause said bolt to project through said opening; an indicator plate secured to the body 105 of the automobile; and connections between said means and the indicator plate whereby the lock may be operated from the seat of the car.

In witness that I claim the foregoing I 110 have hereunto subscribed my name this 29th day of May, 1913.

SELDEN P. HOVEY.

Witnesses:

FRANK WATERFIELD,
MARSHALL TILDEN.
